Byron H. Carpenter.

UNITED STATES PATENT OFFICE

LOUIS HAASE, OF MANHASSET, NEW YORK, ASSIGNOR TO FAIRCHILD AIRPLANE
MANUFACTURING CORPORATION, OF FARMINGDALE, NEW YORK, A CORPORATION
OF NEW YORK

PONTOON NOSE BUFFER

Application filed January 26, 1928. Serial No. 249,606.

- This invention relates to nose buffers in general and in particular to nose buffers for seaplane pontoons, flying boats, and small power boats and the like.
- 5 This class of craft is subject to a great deal of bumping against docks and floats. Such contacts often damage the nose of the craft and necessitate extensive repairs which, are expensive and difficult to make. Further, it is difficult to finish off the nose in good streamline form.
- 10 It is an object of this invention to provide a nose section which is readily detachable and interchangeable and which completes the streamline of the nose of the object to which it is attached and also serves as a resilient buffer.
- 15 Another object of this invention is to provide a nose buffer which is durable in construction, efficient in operation, and cheap of manufacture.
- 20 Another object of this invention is to provide a nose buffer in which the buffering action of resilient material and springs is combined.
- 25 Other objects and advantages of this invention will become apparent from the following specification, claims and appended drawings in which:—
- Fig. 1 is a view showing my improved buffer attached to a seaplane pontoon.
- 30 Fig. 2 is a section view of my buffer in place on a seaplane pontoon.
- Fig. 3 is a front elevation view of a seaplane pontoon constructed to receive the buffer of my invention.
- 35 Fig. 4 is a detail view showing the construction and method of attaching the nose buffer.
- 40 Fig. 5 is a perspective view of the nose buffer partly from the rear.
- Referring to the drawings, I have illustrated the nose buffer of my invention applied to a seaplane float but I do not desire to limit myself to this construction as the nose buffer is equally applicable to flying boats and other marine crafts such as hydroplanes and various sizes of other power crafts. The main feature of this invention is to provide an efficient detachable nose buffer which will complete the streamline of the front of the object to which it is attached.
- As shown in Figs. 2, 4 and 5, the nose buffer is provided with a baseboard 1. On this baseboard 1 and extending outwardly from the front side thereof is a quantity of kapok, cork, sponge rubber, felt or other suitable material held in place as shown in Figs. 2 and 4 by a covering 2. This covering may be made of linen, canvas, netting, straps, or in any other suitable manner and is secured in place by lapping over the sides of the baseboard 1 and is tacked to the back thereof. On top of this covering 2 is another layer of material similar to that within the covering 2 and held in place by a covering 3 similar to covering 2 and secured to the baseboard 1 in a manner similar to that by which the covering 2 is attached. Upon this covering 3 another layer of resilient material is positioned and held in place by a suitable covering 4 secured to the baseboard 1 in a manner similar to that employed with the coverings 2 and 3. The covering 4 forms an outer covering of the buffer and may be formed of canvas, rawhide, or other suitable material. If desired inflated bags may be used in place of any or all the resilient materials above named.
- The bumper may be formed to conform with and complete the streamline of the body to which it is attached by any suitable method. In practice I have found that the resilient material may be readily brought to proper shape in moulds or by cross tacking with cords, etc. The outer covering material may be formed in suitably shaped dies to produce the streamline form and hold the resilient material in this shape. In practice I have found it desirable to form each layer but I do not desire to limit myself in this respect as I am aware that if desired it may be brought to proper shape by forming only part of the layers, for instance the outer layers. The streamline of the buffer is, of course, designed to conform and to complete the streamline of the body to which the buffer is attached. I wish it to be understood that I do not desire to limit myself in any way in respect to the resilient material employed, nor do I wish to limit myself to the use of

a single resilient material since it is obvious that the various layers may be formed of different resilient materials or a plurality of different resilient materials may be combined in any single layer or in all layers. 5 I further wish it to be understood that the buffer may be formed with a single layer of resilient material if desired.

The nose buffer of this invention may be attached to the nose of the float for which it is designed in a great many ways. In practice, I have found the method illustrated in the drawings to be not only efficient but simple in connection with seaplane pontoons. 10 In the drawings I have illustrated the buffer as attached to the nose of a pontoon of the metal type in which a wood frame is employed and a surface of metal. In Fig. 1, I have designated the metal surface generally 15 by the numeral 8. The pontoon proper as shown in Fig. 3, ends abruptly with a nose bulk head 9, thus producing a strong and rigid end which is cheap of manufacture and rugged in construction. 20

In the drawings the plates of the lower surface of the pontoon are shown extending slightly forward of the nose bulk head 9 thus forming a substantially V-shaped ledge at the front of the bulk head 9. Across the 25 arcuate top of the bulk head 9 an overlap strip 10 is provided extending a short distance in front of the bulk head and forming together with the overhang of the bottom plate, a recess in which the base of the nose buffer is adapted to snugly fit. I do not 30 wish to limit myself to this construction as the overhang may be omitted if desired. I also do not wish to limit myself to a flat bulk-head as it is obvious that the bulk head may 35 be of any desired shape. In practice it has been found desirable in many cases to slope the bulk head backward at either side of the center line of the pontoon. In this case the 40 buffer will, of course, protect the sides of the nose to a much greater extent. The pontoon nose may if desired even be closed by a re-entrant bulk head thus facilitating attachment of the bulk head and at the same time providing a greater thickness of buffer. The 45 buffer is shown secured to the pontoon with the baseboard 1 lying against the bulk head 9 by a plurality of screws 9' extending from the inside of the bulk head 9 thru the frame members 8' of the pontoon and into the base- 50 board 1 of the buffer. I am fully aware that the nose buffer might well be attached in other manners, for instance, by bolting the same to the front of the bulk head 9. This 55 method lends itself admirably to the small hydroaeroplanes and floats in which wood construction is used. The buffer may if desired be permanently attached to the pontoon. 60

If desired, a spring 11 or a plurality of 65 springs may be incorporated in the inner

layer of resilient material as shown in Fig. 2. When springs are employed I find it advisable to provide a patch 12 of suitable material between the spring and the linen covering 2. It is, of course, advisable to furnish 70 suitable attaching means 13 between the springs 11 and the baseboard 1.

From the foregoing description it is apparent that the buffer of this invention provides an efficient means for finishing the nose 75 of pontoons, flying boats, and the like in streamline form and at the same time providing a dependable buffer which is quickly detached and replaced. The replaceable feature of the buffers is very important as it 80 permits the replacement of a damaged buffer with a new one without even removing the craft from the water. This results in a great saving of time and expense and keeps the craft in operation whereas with the construction 85 now commonly used, a repair would consume a great deal of time and money and keep the craft out of service for a considerable period.

Various changes in the construction of 90 the embodiment illustrated in the drawings may be made without departing from the spirit of the invention, and I do not therefore desire to limit myself to the specific construction shown and described but to interpret the invention broadly within the scope 95 of the appended claims.

What I claim as my invention is:

1. The combination in a body having a streamline end of a detachable resilient buffer member forming the outer part of said end and completing the streamline in all exposed directions. 100

2. The combination with a body adapted to be propelled thru a fluid medium and having a substantially blunt forward end of a resilient buffer member detachably secured to said forward end and completing the streamlines of said body in all directions. 105

3. In a buffer member of the class described, a base member, a resilient device secured to said base member and projecting outwardly therefrom, a resilient material secured to said base member and projecting outwardly therefrom adjacent said resilient device, and a covering secured to said base member and enclosing said resilient material and device and giving thereto a streamline shape. 110

4. In a nose buffer of the class described, a base member, a plurality of layers of resilient material secured to said base member and positioned and arranged to a streamline form, and a covering shaped to the same streamline form enclosing said layers and secured to said base member. 120

5. The combination in a flotation means for aircraft a resilient end buffer detachably secured to and forming a part of said flota- 125

tion means and completing the aerodynamic streamlines thereof.

6. The combination in a seaplane pontoon having a substantially streamline form of a 5 detachable nose buffer section for absorbing shock and completing the streamline of the pontoon nose.

7. The combination in a flotation body having a substantially streamline form of a de- 10 tachable resilient nose buffer section for absorbing shocks and completing the nose streamlines of the body.

8. In an aircraft flotation means, a nose 15 bulkhead, a nose buffer section including a base adapted to be secured to the nose bulkhead, a resilient means secured to said base, and a cover secured to said base enclosing said resilient means and formed to complete the streamline of the nose of the flotation means.

20 In testimony whereof I affix my signature.
LOUIS HAASE.
